UNITED STATES PATENT OFFICE.

FRANCIS J. RIPPL AND FRANK J. MALLOY, OF CLEVELAND, OHIO, ASSIGNEES TO
GENERAL ELECTRIC COMPANY, A CORPORATION OF NEW YORK.

AUTOMATIC FLARE MACHINE.

Application filed July 8, 1921. Serial No. 483,334.

To all whom it may concern:

Be it known that we, FRANCIS J. RIPPL and FRANK J. MALLOY, citizens of the United States, residing at Cleveland, in the county of Cuyahoga, State of Ohio, have invented certain new and useful Improvements in Automatic Flare Machines, of which the following is a specification.

Our invention relates to lamp making machines and more particularly to automatic machines for making flares for incandescent lamps.

Our object is to provide an automatic machine for the production of flares from substantially long lengths of glass cylinders or tubing. In this specification, a flare will be understood to mean a piece of glass stem tubing on which a flare has been formed.

Heretofore, flares have been made from glass tubing which has been cut to length before flanging. An automatic machine for making flares is disclosed in Fagan Patent No. 866,347, September 17, 1907. However, in machines of this type, labor must be used to cut glass tubes of proper length from glass tubing. The glass tubes must then be properly placed in a hopper for feeding to the automatic flare machine.

In the machine embodying our invention, the uncut lengths of glass tubing are placed in suitable holding means and the ends of the tubing successively subjected to the various operations necessary to the proper flanging of the flare. The flare is then cut off from the glass tubing in the proper lengths by an improved glass cutting means.

More specifically, we have provided a carrier containing a series of suitable holding means for glass tubing and means for rotating the glass tube holding means. In proper sequence in the path of the end of the glass tubing, we have provided means for heating the end of the tubing, means for flanging the end of the tubing, means for gauging the length of the flare to be cut from the tubing, and means for cutting the flare from the tubing.

We are enabled to use long lengths of glass tubing without previous preparation and to secure a comparatively high rate of production of finished flares with a very

small percentage of imperfect flares. The flares are uniform in length and the flanges thereof show practically no variations in shape or size.

In the accompanying drawings, Fig. 1 is a perspective view of a machine embodying our invention;

Fig. 2 is an elevation of the base of said machine showing a portion of the driving mechanism;

In general terms, the operation of the various methods of cutting off a flare is as follows:

In general terms, the operation of the machine is as follows: A piece of glass tubing 10, Fig. 1, is placed in each of a series of rotating chucks A (see also Figs. 6 and 7) which are mounted on the carrier 11 more fully described hereinafter. The carrier 11 is so driven that each of the chucks A is intermittently advanced through a predetermined path in which a sequence of operations is performed upon the end of the glass tubing held in the chuck. Thus the glass tubing 10 is rotated about its own axis by the chuck and about an external axis by the carrier. At the first position, or position B, Fig. 3, the tubing is given a preliminary heating in the predetermined zone of cut-off by a gas burner 12. The tubing is then advanced to position C where it is further heated locally by the gas burners 13. At position D, to which the tubing is now brought, an intensive heat is applied to the zone of cut-off by the gas burners 14.

The gas burner 15 heats the zone of cut-off at position E while the cutting off mechanism F (shown in Figs. 13 to 22, inclusive) removes a section of tubing from the lower end of the tubing 10. In the present machine, the section of tubing removed is a flare 16 (Fig. 1) suitable for use in the manufacture of incandescent lamps. The flare 16 is discharged into a vibrating chute FC (Fig. 3) which delivers it to a suitable container.

The tubing 10 is now advanced to the position G where an intensive heat is applied to the lower end of the tubing by the gas burners 19, Fig. 3. The tubing is then

moved to position H where it is further heated by the gas burners 20 while being flanged by the flanging mechanism K, (shown in Figs. 23, 24, and 25 inclusive).

At position L, the flanged tubing is permitted to cool and is then advanced to position M where the chuck A is opened by mechanism N (shown in Figs. 6, 7 and 8) and the tubing 10 lowered and gauged by the mechanism P. After the tubing has been gauged so that the proper length of flare 16 will be cut from tubing 10 at position E, the chuck A is permitted to close and is advanced to position B where a repetition of the cycle just described is begun. 70 75 80

The drive of the machine is effected by the motor 21 (Figs. 1 and 2) which is mounted in the base 22. The motor 21 through a belt 23 drives the countershaft 24 which is also mounted in the base 22. The countershaft 24 through the belt 25 drives the main driving shaft 26 (Figs. 3 and 4) which is suitably supported on the brackets 27 and 28 in the base 22. A safety connection is provided between the belt 25 and the main driving shaft 26 to prevent injury to the machine as a whole should any of the mechanisms become jammed. This connection consists of the gear 29 (Figs. 3, 4 and 5) fastened to the shaft 26 and rotatably carried on the shaft 26 a pulley 29^a which is driven by the belt 25. Inserted in the lug 29^b on the hub extension of the pulley 29^a is hardened steel plug 29^c which has a slot 29^d therein for receiving a soft steel bar 29^e held in place by the set screw 29^f. The gear 29 has a hardened steel plug 29^g, similar to the plug 29^c, inserted in the hub thereof so as to receive the soft steel bar 29^e in a slot 29^h. When the pulley 29^a is driven by the belt 25, the soft steel bar 29^e causes the gear 29, and the attached shaft 26 to be rotated under ordinary circumstances. However, should any of the operating mechanisms become jammed, the driving means tends to stall and puts a greater burden upon the soft steel bar 29^e which is thereupon sheared between the edges of the hardened steel plugs 29^c and 29^g automatically relieving the strain upon the operating mechanisms and the driving means by permitting the pulley 29^a to be freely rotated upon the shaft 26. The safety connection is again placed into operative condition by removing the broken steel bar 29^e and inserting a new one in its place.

The gear 29, fastened to the main shaft 26, meshes with a gear 30 (Figs. 2, 6 and 8) fastened to the intermediate shaft 31 which is supported from the base 22 by the brackets 32 and 33. To the inner end of the shaft 31 is fastened a bevel gear 34 (Fig. 6) which meshes with and drives the bevel gear 35 (Figs. 6 and 9) fastened to the lower end of the vertical shaft 36 which is rotatably supported in the tubular shaft 130

37. To the upper end of the shaft 36 is fastened a large gear 38 (Fig. 6) which meshes with and drives each chuck A as more fully described hereinafter. The tubular shaft 37 is suitably supported in the base 22 and the column 39 mounted thereon and has fastened to its upper end the carrier 11 previously mentioned. The tubular shaft 37 and carrier 11 are indexed by means 10 of a Geneva gear 40 (Figs. 6, 9 and 11) which is attached to the lower end of the shaft 37 and which has a locking disc 41 fastened to its upper side. The Geneva gear 40 is driven by the Geneva pinion 42 (Figs. 9, 10 and 11) which is fastened to the vertical shaft 43 suitably mounted in the support 44 fastened to the under side of the base 22. A gear 45, rotatably held on the shaft 43 and continuously driven by the gear 46 fastened to the vertical shaft 36, drives the Geneva pinion 42 through the clutch 47 which slides on the shaft 43 and which is connected to the Geneva pinion 42 by a pin 48 fastened in the pinion 42 and 25 working in a recess 49 in the clutch 47. A recess 50 in the clutch 47 is intermittently brought into engagement with a pin 51 fastened to the gear 45, in order to drive the Geneva pinion 42, by the action of the cam 30 52 fastened to the cam shaft 53 suitably supported by brackets fastened to the base 22 and driven from the intermediate shaft 31 by the gear 54 (see Figs. 2, 3 and 6) thereon which drives the gear 55 on the cam 35 shaft 53 through the idler gear 54' mounted on the shaft 55' carried in the base 22. The action of the cam 52 (Figs. 9 and 10) is transmitted through the lever 56 which is pinned at 57 to the bracket 58 and which 40 has pinned near the middle thereof a roller 59 which rides on the cam 52. The lower end of the lever 56 is pinned to a link 60 whose other end is connected to a lever 61 fastened to the shaft 62 carried in the support 44. To the shaft 62 is fastened a yoke 63 which engages a groove 64 in the clutch 47 so as to control the vertical position of the clutch on the shaft 43. A spring 65 fastened to the link 60 and to the base 22 45 tends to hold the roller 59 against the cam 52. The outline of the cam 52 is such that once every revolution thereof the lever 56 swings in toward the cam 52 and, through the link 60, lever 61, shaft 62 and yoke 63, forces the clutch 47 downward so that the recess 50 therein engages the pin 51 on the continuously rotating gear 45 to drive for 50 one revolution thereof the clutch 47 and, through the pin 48, the Geneva pinion 42 which in turn drives the Geneva gear 40. The Geneva gear 40 through the tubular shaft 37 to the upper end of which is attached the carrier 11 advances the chucks A 55 mounted thereon through an angle sufficient to move them from one position to the suc- cessive position. As the single revolution of the Geneva pinion 42 is completed, the cam 52 moves the lever 56 outward therefrom which causes the yoke 63 to lift the clutch 47 to bring the recess 50 out of engagement with the pin 51 on the continuously rotating gear 45. A pair of springs 67 (Fig. 10) carried in recesses 68 in the gear 45 receives the thrust of the clutch 47 when it engages with the gear 45. 70

In order to insure the stopping of the carrier 11 with the chucks A in the exact predetermined positions for the several steps of the operation as previously described, the locking disc 41, previously mentioned, is attached to the upper surface of the Geneva gear 40 (Figs. 9, 10 and 11) and has a series of notches 69 in the periphery thereof corresponding to the number of positions on the machine. One of these notches 69 is engaged by the nose 70 on one arm of a crank 71 mounted on the pin 72 fastened in the support 44. A spring 73 fastened to the other arm of the crank 71 and to the support 44 tends to hold the nose 70 in engagement with a notch 69. As the Geneva pinion 42 begins to engage the Geneva gear 40 for the rotation thereof, the nose 70 is removed from engagement with the notch 69 by a cam-like projection 74, fastened to the Geneva pinion 42, which strikes a projection 75 (see also Fig. 12) fastened in an arm of the crank 71 so that the crank 71 is forced away from the locking disc 41. As soon as the Geneva gear 40 and attached 80 locking disc 41 have been rotated by the Geneva pinion 42 through an angle sufficiently large to prevent the engagement of the nose 70 with the notch 69 which it has just released, the projection 74 on the pinion 42 releases the projection 75 on the crank 71 thus permitting the crank 71 to return toward the locking disc 41 bringing the nose 70 into position to engage the succeeding notch 69 as it is rotated into place. 85 The projection 75 may be adjusted to change the relative time at which it is engaged by the projection 74 by adjusting the screw 76 (Fig. 12) which is seated in the projection 75 and which screws into the hub of the crank 71. When properly adjusted the projection 75 is fastened into place by the bolt 77 which passes through a slot 78 in the projection 75 and screws into an arm of the crank 71. 90

Cutting off mechanism.—As previously described, the glass tubing 10 with the flange on the lower end thereof is heated on the line of cut-off in the positions B, C and D and also in the cutting-off position E (see Fig. 3). The cutting-off mechanism F (see Fig. 1) comprises mechanism FA (Figs. 20, 21 and 22) for holding and synchronously rotating the flare which is being cut from the glass tubing 10 and mechanism FB 100

110

115

120

125

130

(Figs. 16, 17, 18 and 19) for performing the actual cutting off of the flare in the pre-heated zone. Briefly, the operation is carried out as follows: The gauged and lowered glass tube 10, which has previously been flanged and preheated in the zone of cut-off as described hereinafter, is advanced by the carrier 11 into the position E. Immediately the chuck mechanism FA acts to hold the lower end of the tubing 10 and to rotate it synchronously with the upper end, the tubing 10 having an intermediate softened portion due to the heating in the zone of cut off. The cutting mechanism FB then operates to cut the tubing 10 leaving the flare F¹⁰ (Fig. 1) in the chuck FA. Thereupon the chuck FA releases the flare F¹⁰ which is discharged into a chute FC which delivers it to a suitable container. In order to simplify the description, each part of the mechanism will be described separately giving the drive the letter F of the cutting off mechanism as a whole; the tubing holding means or chuck, the letters FA; the means for cutting the tubing, the letters FB; and the delivery chute, the letters FC; in each case the proper letters being coupled with suitable numerals.

The cutting off mechanism drive is effected from the main driving shaft 26 by a bevel gear F¹¹ (Figs. 4 and 13) attached thereto which meshes with and drives a bevel gear F¹² (Fig. 13) fastened to the vertical shaft F¹³ which has suitable bearings in the housing F¹⁴ and the bracket F¹⁵ to which the housing F¹⁴ is attached. The bracket F¹⁵ is fastened to the base 22. A gear F¹⁶ (Figs. 13, 16 and 18) rotatably held on the upper end of the shaft F¹³ is normally caused to rotate therewith by the friction clutch F¹⁷ fastened to the shaft F¹³ so as to drive the chuck FA as described hereinafter (Fig. 18). The clutch F¹⁷ has a leather faced disc F¹⁸ driven by a pin F¹⁹ fastened in the clutch and held against the gear F¹⁶ by a spring F²⁰ carried in a recess in the clutch F¹⁷. A leather disc F²¹, between the gear F¹⁶ and the retaining screw F²² fastened in the end of the shaft F¹³, also tends to rotate the gear F¹⁶ with the shaft F¹³.

To the lower end of the shaft F¹³ is also fastened a gear F²³ (Figs. 13 and 14) which effects the drive of each of the two cutters which form a part of the cutting mechanism FB as more completely set forth hereinafter. The gear F²³ drives the idler gear F²⁴ (see also Fig. 15) which is rotatably mounted on the pin F²⁵ fastened in the housing F¹⁴. At this point in the drive, provision is made for changing the speed of rotation of the cutters relative to the speed of rotation of the chucks by the following described means. The gear F²⁴ drives another idler gear F²⁶ which is rotat-

ably carried on a pin F²⁷ mounted in an arm of the member F²⁸ which is pivoted on the pin F²⁵ and locked into position by a bolt F²⁹ which screws into the housing F¹⁴ and which works in a slot F³⁰ on the other arm of the member F²⁸. Various sizes of gears may be substituted for the gear F²⁶ to secure the desired speed of rotation. The member F²⁸ is so positioned that the gear F²⁶ meshes with and drives a gear F³¹ mounted on the short vertical shaft F³² suitably mounted in the housing F¹⁴. Near the upper end of the shaft F³² is fastened a gear F³³ which drives the gear F³⁴ rotatably carried on the shaft F¹³. The gear F³⁴ drives a gear F³⁵ (see also Figs. 18 and 19) with tubular hub extension F³⁶ which is rotatably mounted in the bracket F²⁷ more fully described hereinafter. The gear F³⁵ drives the smaller of the two cutters as hereinabove described.

Just above the gear F³³ on the shaft F³² is fastened a bevel gear F³⁸ (Figs. 13 and 14) which drives the bevel gear F³⁹ fastened on the horizontal shaft F⁴⁰ suitably carried in the housing F¹⁴. On the end of the shaft F⁴⁰ opposite to the gear F³⁹ is fastened a worm gear F⁴¹ which drives a worm wheel F⁴² fastened on the vertical shaft F⁴³ mounted in the housing F¹⁴. Below the worm wheel F⁴² and on the shaft F⁴³ is fastened a gear F⁴⁴ which drives the gear F⁴⁵ (see also Fig. 19) connected to the larger of the cutters as more fully described hereinafter.

The chuck mechanism includes a main member FA¹⁰ (Figs. 20, 21 and 22) which is carried on a ball race FA¹¹ mounted in an arm FA¹² of the bracket FA¹³ mounted on the base 22. Around the periphery of the upper part of the main member FA¹⁰ is cut a gear FA¹⁴ which meshes with and is driven by the gear F¹⁶ (see Figs. 13, 16 and 18) previously described. Fastened to the pin FA¹⁵ (Fig. 22) which is carried in the lugs FA¹⁰ (Fig. 20) on the top of the member FA¹⁰, is a vertical arm FA¹⁷ which has at its upper end a V-shaped engaging finger FA¹⁸. To the end of the pin FA¹⁵ is fastened a horizontal arm FA¹⁹ whose end is rounded and has teeth FA²⁰ which mesh with similar teeth FA²¹ on the end of the horizontal arm FA²² similar to arm FA¹⁹ and fastened to the end of the pin FA²³ (see also Fig. 21) carried in the lugs FA²⁴ on the main member FA¹⁰. A vertical arm FA²⁵ similar to the arm FA¹⁷ is fastened to the pin FA²³ and fastened to the upper end of the arm FA²⁵ is a V-shaped engaging finger FA²⁶ similar to the finger FA¹⁸. Through the teeth FA²⁰ and FA²¹ the motion imparted to one engaging finger is correspondingly imparted to the other engaging finger. A spring FA²⁷, fastened at the middle to a pin FA²⁸ mounted on the member FA¹⁰ and at each end to the horizontal arms FA¹⁹ 130

120
125
130

and FA²², tends to close the engaging fingers FA¹⁸ and FA²⁶ toward each other. The engaging fingers FA¹⁸ and FA²⁶ are caused to separate as follows: A rod FA²⁹ (Fig. 22) is seated at its upper end in the horizontal arm FA¹⁹ being vertically aligned in a suitable hole in the main member FA¹⁰ and has a roller FA³⁰ pinned in its lower end. The roller FA³⁰ rides on the surface of a ring-shaped arm FA³¹ disposed concentric with the main member FA¹⁰ and fastened to a vertical rod FA³² which is slidably supported in the bracket FA¹³. A spring FA³³ (Figs. 21 and 22) mounted around the rod FA³² between the stop FA³⁴ fastened thereto and the base 22 tends to hold the rod FA³² in a lowered position which may be regulated by adjusting the position of the arm FA³¹ relative to the rod FA³². The angular alignment of the rod FA³² is maintained by an arm FA³⁵ fastened to the lower end thereof and having in its other end a slot which receives the pin FA³⁷ mounted in the base 22. The rod FA³² is raised to force the rod FA²⁹ upward by means of the arm FA³¹, and thereby to cause the separation of the engaging fingers FA¹⁸ and FA²⁶, by the action of a cam FA³⁸ fastened to the cam shaft 53. The action of the cam FA³⁸ is transmitted to the rod FA³² by the crank FA³⁹ which is pivoted on the pin FA⁴⁰ mounted in the base 22 and which has on one arm a roller FA⁴¹ riding on the cam FA³⁸ and on the other arm an adjustable bolt FA⁴² which engages the rod FA³² to raise the same when so acted upon by the cam FA³⁸. The amount of lift given to the rod FA³² by the bolt FA⁴² may be regulated by adjusting the bolt FA⁴² in the arm of the crank FA³⁹. The contour of the cam FA³⁸ is such that once during every revolution the engaging fingers FA¹⁸ and FA²⁶ are caused to be separated and then are permitted to be brought together again by the action of the spring FA²⁷.

As previously stated, the rotation of the chuck FA is stopped after the flare F¹⁰ has been cut off to permit the discharge of the same and to permit the indexing of the succeeding glass tubing 10 into position. The chuck is opened after its rotation has been stopped for the discharge of the flare and is closed again after it has started to rotate. The chuck is preferably stopped in a predetermined position to permit the proper discharge of the flare F¹⁰ and to provide clearance between the engaging fingers FA¹⁸ and FA²⁶ and the succeeding glass tubing 10. The position of stopping is preferably with the common center line of the two engaging fingers FA¹⁸ and FA²⁶ perpendicular to the path of rotation of the glass tubing 10. The stopping of the chuck is effected in the following manner. A projection FA⁴³ (Fig. 20) is fastened to the upper surface of the main member FA¹⁰ so that it may be engaged by the head of a plunger FA⁴⁴ which works in a corresponding recess in the arm of the crank FA⁴⁶ which is pivoted at FA⁴⁷ on the bracket FA¹³. A spring contained in the recess of the crank FA⁴⁶ between the bottom thereof and the plunger FA⁴⁴ absorbs the shock when the projection FA⁴³ suddenly strikes the head of the plunger FA⁴⁴ which is caused as explained hereinafter. The plunger FA⁴⁴ tends to engage the projection FA⁴³ through the action of a spring FA⁴⁹ fastened to an arm of the crank FA⁴⁶ and to the housing which encloses a large portion of the cutting off mechanism above the base 22 and which is not shown in the drawings. The amount of the projection FA⁴³ engaged by the plunger FA⁴⁴ may be regulated by adjusting the bolt FA⁵⁰ (Fig. 21) which works in one arm of the crank FA⁴⁶ and butts against the pin FA⁵¹ fastened in the bracket FA⁵² mounted on the base 22. The plunger FA⁴⁴ is caused to release the projection FA⁴³ by the action of a cam FA⁵³ fastened to the cam shaft 53. The action of the cam FA⁵³ is transmitted through a crank FA⁵⁴ pivoted on the pin FA⁴⁰ and having in one arm a roller FA⁵⁵ riding on the cam FA⁵³ and in the other arm an adjustable bolt FA⁵⁶ which engages a rod FA⁵⁷ slidably supported in the bracket FA⁵² and having a roller FA⁵⁸ (Fig. 20) pinned in the upper end thereof which engages the beveled edge of an arm of the crank FA⁴⁶ to turn the crank FA⁴⁶ about its pivot FA⁴⁷ and thus withdraw the plunger FA⁴⁴ from engagement with the projection FA⁴³ thereby permitting the rotation of the chuck through the friction clutch F²⁰ (Fig. 18) previously mentioned. The rod FA⁵⁷ is normally held in a lowered position by the action of a spring FA⁵⁹ encircling the rod FA⁵⁷ and bearing against a stop FA⁶⁰ fastened thereto and against the base 22. The rod FA⁵⁷ is held in angular alignment by an arm FA⁶¹ attached thereto and having a slot FA⁶² in its end which receives the pin FA³⁷. The amount of upward lift of the rod FA⁵⁷ may be regulated by adjusting the bolt FA⁵⁶ in the arm of the crank FA⁵⁴. The contour of the cam FA⁵³ is such that once every revolution thereof the projection FA⁴³ is released from the plunger FA⁴⁴ to permit the rotation of the chuck and then for a somewhat shorter interval the plunger FA⁴⁴ is permitted to engage the projection FA⁴³ and so stop the rotation of the chuck to permit the discharge of the flare F¹⁰ while the machine is indexed.

The cutters and mechanism.—The flare F¹⁰ (Fig. 19) is cut from the tubing by a small cutter FB¹⁰ on the inside of the glass tubing 10 and a large cutter FB¹¹ on the out-

side of the tubing 10. In general the action of the cutters is as follows: The small cutter FB¹⁰ is raised up inside the tubing 10 as the latter is being engaged by the chuck FA 5 and when the cutter FB¹⁰ is level with the large cutter FB¹¹, the two cutters are gradually brought together to cut off the flare F¹⁰ both cutters being rotated so that the peripheral speed of each cutter is substantially the same as the peripheral speed of the glass surface being cut. After the flare F¹⁰ has been cut off, the two cutters are separated and the small cutter FB¹⁰ being lowered to permit the discharge of the flare F¹⁰ 10 and the indexing of the succeeding glass tubing 10. The small cutter FB¹⁰ is rotated only while in the raised position.

The small cutter FB¹⁰ is mounted in the upper end of the vertical shaft FB¹² which 20 is supported in the following manner. The bracket F¹⁵, previously mentioned, supports a tubular member FB¹⁸ (Figs. 16 and 18) about which is pivoted the sleeve FB¹⁴ of the bracket FB¹⁵, the sleeve FB¹⁴ resting 25 on the bracket F¹⁵. A second bracket F³⁷, previously mentioned, is fastened below the sleeve FB¹⁶ of the bracket FB¹⁵. A tubular member FB¹⁷ (Fig. 19) carried by the sleeve FB¹⁶ provides a suitable bearing for the 30 tubular elevating member FB¹⁸ which is rotatably held on the vertical shaft FB¹² at the lower end by the set-screw collar FB¹⁹ and at the upper end by the taper pin collar FB²⁰. The lower end of the vertical shaft 35 FB¹² is rotatably supported in the hub extension F³⁶ of the gear F³⁵, previously described, the gear F³⁵ being rotatably carried in the lower end of the bracket F³⁷ and being held thereon by the taper pin collar FB²¹. 40 The upper end of the hub extension F³⁶. The vertical shaft FB¹² is driven as follows: The gear F³⁵ has two pins FB²² fastened in its lower side and when the shaft FB¹² is elevated as described hereinafter one 45 of the pins FB²² engages and drives a pin FB²³ fastened in a collar FB²⁴ mounted on the lower end of the vertical shaft FB¹² so that the shaft FB¹² and cutter FB¹⁰ are rotated. The elevation of the cutter 50 FB¹⁰ and the shaft FB¹² is effected through the elevating member FB¹⁸ by the action of the cam FB²⁵ (Fig. 18) mounted on the cam shaft 53. The action of the cam FB²⁵ is transmitted through a lever FB²⁶ which is 55 pivoted at FB²⁷ to the bracket FB²⁸ fastened to the base 22 and which has a roller FB²⁹ riding on the cam FB²⁵. A slot FB³⁰ in the end of the lever FB²⁶ engages a square block FB³¹ which is rotatably mounted on the pin FB³² fastened in the lower end of the elevating member FB¹⁸. The member FB¹⁸ is free to move vertically but the angular alignment thereof is maintained by the 60 guides FB³³ and FB³⁴ mounted on the bracket F³⁷ and engaging grooves on the 65

lower end of the member FB¹⁸. A spring FB³⁶ fastened to the lever FB²⁶ and to a rod FB³⁷ mounted on the base 22 tends to hold the elevating member FB¹⁸ in a lowered position. The contour of the cam FB²⁵ is such that during the revolution thereof the small cutter FB¹⁰ is caused to be elevated for cutting the tubing which elevation causes the engagement of the driving means of the cutter as previously explained. After an interval during which the flare F¹⁰ is cut off from the tubing the small cutter FB¹⁰ is caused to be lowered to provide clearance. 75

The large cutter FB¹¹ (Fig. 19) is held 80 between the plates FB³⁸ and FB³⁹ which are mounted on the vertical shaft FB⁴⁰ between the taper pin collar FB⁴¹ fastened thereto and the nut FB⁴² which screws on the end of the shaft FB⁴⁰. The shaft FB⁴⁰ is rotatably carried in the sleeve FB⁴³ mounted in the bracket FB⁴⁴ which is pivoted about the tubular member FB⁴⁵ (see Fig. 16) which is a part of the bracket F¹⁵ previously mentioned. The shaft FB⁴⁰ is driven by the gear F⁴⁶, previously described, which is fastened to the lower end thereof. 90

In order to provide clearance the two cutters FB¹⁰ and FB¹¹ are normally separated but when prepared to cut are permitted to advance toward each other. This action of the cutters is effected in the following manner. On the edge of the bracket FB¹⁵, which carries the small cutter FB¹⁰, is a groove FB⁴⁶ (Fig. 18) which receives the member FB⁴⁷ (see also Figs. 16 and 17). A bolt FB⁴⁸ working in the slot FB⁴⁹ (Fig. 16) in the member FB⁴⁷ fastens the member FB⁴⁷ to the bracket FB¹⁵. The head of the set-screw FB⁵⁰ which screws into the bracket FB¹⁵ bears against the end of the member FB⁴⁷ and assists in positioning this member in the groove FB⁴⁶. The inner end of the member FB⁴⁷ has pinned therein a roller FB⁵¹ (Fig. 16) which rides upon the inclined surface FB⁵² (Fig. 17a) of the wedging bar FB⁵³. Riding on the opposite inclined surface FB⁵⁴ of the wedging bar FB⁵³ is a roller FB⁵⁵ pinned in the member FB⁵⁶ which is held in the groove in the end of the bracket FB⁴⁴ by a bolt FB⁵⁸ working in a slot FB⁵⁹ in the member FB⁵⁶ which is similar to the member FB⁴⁷. The head of the set-screw FB⁶⁰ which screws into the bracket FB⁴⁴ bears against the end of the member FB⁵⁶ and assists in positioning the member FB⁵⁶ in the groove. A spring FB⁶¹ fastened to the pin FB⁶² mounted on the bracket FB⁴⁴ and to the pin FB⁶³ (Fig. 17) mounted on the bracket FB¹⁵ tends to draw the two brackets together swinging the brackets FB¹⁵ about the tubular member FB¹⁸ and the bracket FB⁴⁴ about the tubular member FB⁴⁵. This action of the spring FB⁶¹ is normally pre- 130

vented by the wedging bar FB⁵³ which separates the rollers FB⁵¹ and FB⁵⁵ but which is withdrawn in the following manner to permit the advance of the cutters FB¹⁰ and FB¹¹ when they are in position to cut the flare F¹⁰ from the glass tubing. The wedging bar FB⁵³ is slidably mounted in a guiding bracket FB⁶⁴ (Fig. 17) which is mounted free to move horizontally in a bracket 10 FB⁶⁶ fastened to the base 22. A spring FB⁶⁶ fastened to a pin FB⁶⁷ on the wedging bar FB⁵³ and to a pin FB⁶⁸ on the guiding bracket FB⁶⁴ tends to withdraw the wedging bar from between the rollers FB⁵¹ and FB⁵⁵ but is normally prevented from so doing by the action of a cam FB⁶⁹ mounted on the cam shaft 53. The action of the cam FB⁶⁹ is transmitted through the crank FB⁷⁰ which is pivoted at FB⁷¹ in the bracket 20 FB⁶⁵. The crank FB⁷⁰ has pinned in one arm a roller FB⁷² riding on the cam FB⁶⁹ and has fastened in the other arm an adjustable bolt FB⁷³ which engages the lower end of the wedging bar FB⁵³ to raise the bar 25 when so acted upon by the cam FB⁶⁹. The engagement of the bolt FB⁷³ with the wedging bar FB⁵³ may be regulated by adjusting the position of the bolt FB⁷³ in the arm of the crank FB⁷⁰. The contour of the cam 30 FB⁶⁹ is such that the wedging bar FB⁵³ is normally held up to separate the brackets FB¹⁵ and FB⁴⁴ until the cutters FB¹⁰ and FB¹¹ are in position to act whereupon the wedging bar FB⁵³ is permitted to be withdrawn by the action of the spring FB⁶⁶. The amount of withdrawal of the wedging bar FB⁵³ is determined by the position of the adjustable bolt FB⁷⁴ (Figs. 17 and 17^a) which screws in the arm FB⁷⁵ fastened to 35 the upper end of the wedging bar and which strikes against the top of the guiding bracket FB⁶⁴ to limit the downward movement of the bar FB⁵³. The amount of withdrawal may be regulated by adjusting the bolt FB⁷⁴ in the arm FB⁷⁵.

The horizontal position of the cutters FB¹⁰ and FB¹¹ relative to the glass tubing 10 may be regulated by adjusting the rod FB⁷⁶ (Figs. 16, 17 and 17^a) which has a head FB⁷⁷ projecting outside the base 22 and which has a threaded portion working in a thread in the guiding bracket FB⁶⁴ and whose end is rotatably held at FB⁷⁸ in the bracket FB⁶⁵. The action of the rod FB⁷⁶ is such that the guiding bracket FB⁶⁴ is moved horizontally along the slide FB⁷⁹ on the bracket FB⁶⁵, the brackets FB¹⁵ and FB⁴⁴ being moved about their respective pivots by the presence of the wedging bar FB⁵³ between their respective rollers. By properly adjusting the horizontal position of the cutters FB¹⁰ and FB¹¹ relative to the glass tubing 10, the upper end of the flare F¹⁰ may be made substantially flush with the main portion of the tube, may be turned inwardly

or outwardly as shown in Fig. 26. It is believed that an advantage exists in turning the upper end of the flare slightly outwardly as shown in C of Fig. 26 when leading-in wires are loaded through the flare 70 on the usual stem making machines. This also prepares the glass tubing for the subsequent flaring operation.

The flare F¹⁰, which is cut from the glass tubing 10 at the position F, when released by the engaging fingers FA¹⁸ and FA²⁶ (Fig. 22) falls upon an incline FC¹⁰ (Fig. 1) which is fastened to the main member FA¹⁰ of the chuck and which slants toward the discharge chute FC¹¹ (Figs. 1 and 3) to be delivered to a suitable container FC¹² mounted on a side of base 22. An air jet FC¹³ (see Fig. 3) which is suitably supported on the base 22 directs a stream of air upon the flare F¹⁰ to blow the flare 80 into the chute FC¹¹. In order to deliver the flare F¹⁰ into the container FC¹², the chute FC¹¹ is agitated in the following manner. A ball link FC¹⁴ (Fig. 1) has one end held in a socket FC¹⁵ on the chute FC¹¹ and the other end held in an eccentric socket FC¹⁶ mounted on the upper end of the rod FC¹⁷ which is rotatably held in the bracket FC¹⁸ fastened to the base 22. The rod FC¹⁷ is driven from the main driving shaft 26 by 90 means of the belt FC¹⁹ (Figs. 3 and 4) driven by the pulley FC²⁰ on the shaft 26 and driving the pulley FC²¹ on the rod FC¹⁷. A spring FC²² fastened to the chute FC¹¹ and to the bracket FC¹⁸ tends to draw the chute toward the base. The lower end of the chute FC¹¹ is pivoted on a pin FC²³ (see Fig. 3) carried in the bracket FC²⁴ slidably on the base 22 and fastened thereto by the bolt FC²⁵. As the rod FC¹⁷ is rotated the ball link FC¹⁴ working in the eccentric socket FC¹⁶ alternately raises and lowers the chute FC¹¹ about the pivot pin FC²³ producing sufficient agitation to cause the flare 100 F¹⁰ to pass down the inclined surface of the chute FC¹¹ into the container FC¹².

The flanging mechanism.—The lower end of the tubing 10, which has previously been heated at position G as hereinbefore set forth, is flanged by the flanging mechanism K (Figs. 1 and 3) which is located at position H. The flange K¹⁰ (Fig. 25) is accomplished by a pencil K¹¹ (Figs. 23, 24 and 25) mounted in a stirrup K¹² which is pivoted on the two standards K¹³ which are fastened to the cap K¹⁴ on the upper end of the tubular member K¹⁵. The tubular member K¹⁵ is rotatably held in the elevation adjusting member K¹⁶ which screws into a collar K¹⁷ fastened to the standard K¹⁸. A set screw K¹⁹ working in the collar K¹⁷ forces a soft metal plug K²⁰ against the thread of the adjusting member K¹⁶ to lock the latter in place. A thrust ball race K²¹ carried on a flange K²² on the lower end of 130

the tubular member K^{15} takes up the thrust between the flange K^{22} and the adjusting member K^{16} when the tubular member K^{15} is elevated against the adjusting member K^{16} as more fully described hereinafter.

The upper end of each of the two uprights K^{23} is pinned one to each side of the stirrup K^{12} and to the cap K^{24} which is fastened to the upper end of the elevating tube K^{25} . The longitudinal movement of the elevating tube K^{25} relative to the tubular member K^{15} causes a movement of the stirrup K^{12} about the pivots on the standards K^{18} to bring the pencil K^{11} through the successive positions assumed in forming the flange K^{10} on the glass tubing 10. A pin K^{26} fastened in the cap K^{14} and working in a corresponding aperture K^{27} in the cap K^{24} serves as a guide for vertical movement of the cap K^{24} relative to cap K^{14} and also transmits the rotative motion imparted to the elevating tube K^{25} , as hereinafter set forth, to the tubular member K^{15} .

The elevating tube K^{25} is caused to rotate by power transmitted to the pulley K^{28} , fastened to the tube K^{25} , by a belt K^{29} which runs over the idler pulleys K^{30} and K^{31} (see also Figs 1 and 3) fastened to the edge of the base 22 and which is driven by the pulley K^{32} fastened to the motor 21. The tube K^{25} is raised to bring the pencil K^{11} into operative relation with the glass tubing 10 in the following manner. Positioned on the lower end of the tube K^{25} by the collars K^{33} (Fig. 24) and K^{34} is an adjusting member K^{35} which screws into a horizontal plate K^{36} . The plate K^{36} is locked on the member K^{35} by the set screw K^{37} (see Fig. 24a) which wedges a plug K^{38} against the soft metal plug K^{39} to force the plug K^{39} against the thread of the member K^{35} , the plugs K^{38} and K^{39} being held in the plate K^{36} in passages at right angles to each other. A vertical guide rod K^{40} sliding in the standard K^{18} has its lower end fastened in the plate K^{36} to maintain its alignment during the vertical movement thereof. A roller K^{41} is pinned to one end of the plate K^{36} and is held against the cam K^{42} , which is fastened on the cam shaft 53 previously described, by the action of a spring K^{43} fastened to the plate K^{36} and to the base 22. The contour of the cam K^{42} is such that once during every revolution the elevating tube K^{25} is gradually raised through the roller K^{41} and the plate K^{36} . The pulley K^{28} carries upward the helical spring K^{44} resting thereon and bearing against the under side of the flange K^{22} which action tends to force the tubular member K^{15} upward until the thrust ball race K^{21} is brought against the adjusting member K^{16} where the upward movement of the member K^{15} is halted while the upward movement of the elevating tube K^{25} is continued. This further movement of the

tube K^{25} causes the pencil K^{11} to pass through the positions desirable for forming the flange K^{10} on the glass tubing 10. The tube K^{25} is then lowered, the pencil K^{11} returned to a normal position and the tubular member K^{15} also being lowered.

It sometimes happens that the glass tubing 10 breaks while being flanged and the broken off portion of the tube falls around the pencil K^{11} . It is desirable that this broken tube be removed from the pencil K^{11} before the succeeding glass tubing 10 is brought into position for flanging. To accomplish this removal, there is provided a stripping bar K^{45} (Figs. 23 and 24) which is fastened on the upper end of the half-round rod K^{46} carried in the elevating tube K^{25} and normally resting on a shoulder K^{47} therein. A half-round plug K^{48} inserted in the upper end of the tube K^{25} maintains the angular alignment of the rod K^{46} . To the lower end of the rod K^{46} is fastened a rod K^{49} whose lower end strikes the head of an adjustable bolt K^{50} carried in the bracket K^{51} and so arrests the downward movement of the stripping bar K^{45} when the elevating tube K^{25} descends after flanging. The pencil K^{11} thus descends past the stripping bar K^{45} and any broken tubing, which may be lodged thereon, is removed. The adjustable bolt K^{50} may be regulated to alter the position at which the downward movement of the rod K^{49} is arrested. The rod K^{49} tends to be brought into a lowered position relative to the elevating tube K^{25} by the action of a spring K^{52} which encircles the rod K^{49} bearing against the aligning member K^{53} attached thereto and a shoulder K^{54} in the tube K^{25} .

The chuck, lowering and gauging mechanism.—The chuck A (Figs. 1 and 6) holds and rotates the glass tubing 10 as it is advanced to each position by the carrier 11 and worked upon by the several mechanisms. The chuck has a main tubular member A^{10} (Figs. 6 and 7) which is rotatably held in suitable bearings on the carrier 11 by a collar A^{11} fastened to the upper end thereof. The main member A^{10} is continuously rotated by means of a gear A^{12} attached near the upper end thereof and driven by the large gear 38 previously described. A member A^{13} sliding inside the main member A^{10} has attached to its lower end, by links A^{14} , the wedges A^{15} which hold the tubing 10 through a wedging action against the conical surface A^{16} of the ring A^{17} which is inserted in the lower end of the main member A^{10} . The member A^{13} is normally held in a lowered position by the action of a spring A^{18} bearing against its upper end and against a stop A^{19} fastened in the upper end of the main member A^{10} . A collar A^{20} sliding on the main member A^{10} and rotating therewith engages the member A^{13} by means of the two

bolts A²¹ which work in slots A²² in the main member A¹⁰ so that when the collar A²⁰ is raised the wedges A¹⁵ are raised to release the tubing 10. A groove A²³ in the collar A²⁰ receives the rollers A²⁴ mounted on the pins A²⁶ fastened in the arm A²⁸ whose end is pivoted in the member A²⁷ fastened to the tubular shaft 37. When the arm A²⁸ is lifted by the chuck opening mechanism N, the collar A²⁰ is raised relative to the main member A¹⁰ causing the wedges A¹⁵ to be raised to release the glass tubing 10. Upon the release of the chuck opening mechanism N, the spring A¹⁸ causes the wedges A¹⁵ to re-engage the tubing 10. To assist in position the glass tubing 10 in the chuck a guide sleeve A²⁸ is inserted in the main member A¹⁰ and fastened to the stop A¹⁹ in the upper end thereof.

20 The chuck opening mechanism has a vertical lifting rod N¹⁰ (Figs. 6 and 8) which slides in a guiding standard N¹¹ mounted on the base 22. Into the split upper end of the rod N¹⁰ is screwed and locked by the set screw collar N¹² a support N¹³ carrying the roller N¹⁴ which engages the chuck arm A²⁸ to lift the same when the rod N¹⁰ is raised. The rod N¹⁰ is raised by the action of the cam N¹⁵ transmitted through the crank N¹⁶ and the link N¹⁷ which connects the end of one arm of the crank N¹⁶ and the lower end of the rod N¹⁰. The crank N¹⁶ is pivoted at N¹⁸ to a bracket N¹⁹ on the base 22 and in its second arm has a roller N²⁰ which is held against the cam N¹⁵ by the action of a spring N²¹ fastened to the first arm of the crank N¹⁶ and to a pin N²² fastened to the bracket 33 on the base 22. The cam N¹⁵ is fastened to the cam shaft 53 and has a contour such that once every revolution thereof the rod N¹⁰, through the crank N¹⁶ is raised to lift the chuck arm A²⁸ and so open the chuck A to permit the glass tubing 10 to be released while being gauged.

45 As the glass tubing 10 is released the gauging tube P¹⁰ (Figs. 6 and 8) is raised or advanced to receive the flange on the fiber disc P¹¹ to prevent shock or jar to the flange. The disc P¹¹ is fastened to the metal disc P¹² which is fastened to the short rod P¹³ rotatably carried in the flanged member P¹⁴. The flanged member P¹⁴ is inserted in the upper end of the gauging tube P¹⁰ and fastened by the set screw collar P¹⁵. The gauging tube P¹⁰ is slidably supported in an arm P¹⁶ of the guiding standard N¹¹ of the chuck opening mechanism and has inserted in the lower end thereof a gauging rod P¹⁷ which is fastened in the tube P¹⁰ by means of the set screw collar P¹⁸. The gauging rod P¹⁷ is raised or advanced by the action of the spring P¹⁹ fastened to the bracket 33 and to one arm of the crank P²⁰ which is pivoted in the bracket P²¹ mounted on the base 22 and whose other arm is connected by a link P²² to an arm P²³ fastened to the lower end of the gauging rod P¹⁷. The gauging tube P¹⁰ and gauging rod P¹⁷ are caused to be lowered by the action of a cam P²⁴ fastened on the cam shaft 53 and bearing against the roller P²⁵ pinned to an arm of the crank P²⁰. The contour of the cam P²⁴ is such that, once every revolution thereof, the gauging tube P¹⁰ is lowered or returned from its raised or advanced position to 70 gauge the glass tubing 10 by limiting the downward movement of the tubing 10 while the chuck A is open, the flange K¹⁰ resting on the fiber disc P¹¹ which may be rotated in the flange member P¹⁴ by the rotating tubing 10. After the chuck A has closed, the cam P²⁴ releases the roller P²⁵ so that the gauging tube P¹⁰ may be raised by the action of the spring P¹⁹ but the elevation of the tube P¹⁰ is prevented for a time by 75 the presence of the glass tubing 10. When the tubing 10 has been removed from the disc P¹¹ by the indexing of the carrier 11, the gauging tube P¹⁰ is raised by the spring P¹⁹ to receive the released glass tubing 10 80 in the succeeding chuck A thus preventing a shock which might occur should the tubing 10 drop the full distance to the disc P¹¹. In order to permit the making of various lengths of flares, the gauging rod P¹⁷ may be 85 inserted to various distances in the gauging tube P¹⁰ by releasing the set screw collar P¹⁸, a scale P²⁶ being laid off on the gauging rod P¹⁷ to facilitate the proper adjustment of the rod P¹⁷ relative to the tube P¹⁰. The 90 length of the rod P¹⁷ inserted in the tube P¹⁰ determines the distance the tube P¹⁰ will be lowered from the raised position of Fig. 6 and so permits the length of the flare which will be cut off to be regulated at this position. The short ends of tubing P²⁷ are removed from the apparatus by an air jet P²⁸ (Figs. 1 and 6) supported in the standard N¹¹ which directs a stream of air upon the tubing 10 when the gauging tube P¹⁰ is in a lowered position, the short end of tubing 10 is thus blown off the disc P¹¹ into a chute P²⁹ (Fig. 1) which delivers it to a suitable container P³⁰ carried on the base 22.

50 To sum up the operation of the mechanisms at position M on the apparatus, when the gauged glass tubing 10 is advanced from the position M the gauging tube P¹⁰ is automatically raised until the set screw collar P¹⁸ strikes the arm P¹⁶. The succeeding 115 chuck A is indexed into place. The rod N¹⁰ is raised to lift the chuck arm A²⁸ and so open the chuck A. With the flange K¹⁰ of the tubing 10 resting on the disc P¹¹, the tube P¹⁰ is lowered to gauge the length of flare which will be cut off at a succeeding 120 position. The rod N¹⁰ is then lowered and the chuck A is thereby automatically closed. The tubing 10 is then ready to be advanced 125 to the cutting off position.

60 130

While we have described a specific machine embodying our invention, we do not wish to be limited thereto as modifications thereof will readily suggest themselves to those skilled in the art.

What we claim as new and desire to secure by Letters Patent of the United States, is:—

1. An apparatus for flanging a glass tube comprising means for holding said tube, means for rotating said holding means, means for fusing an end of said tube, means for flanging said end, and means for cutting off a section of the tube including the flanged portion without substantially narrowing the passage therethrough.
2. An apparatus for forming a plurality of flares from a length of glass tubing comprising a holder for said tubing, means for fusing an end of said tube, means for flanging said end, means for cutting off a section of said tube including the flare without substantially narrowing the passage therethrough, and means for then advancing said tube in said holder to permit another flanging operation thereon.
3. An apparatus for forming a plurality of flares from a length of glass tubing comprising a carrier supporting a plurality of holders each adapted to receive a length of glass tubing, means for rotating said carrier step by step, a fusing means, a flanging means, and means for severing a section of tubing comprising a flange without substantially narrowing the passage therethrough, all disposed in the path of travel of the ends of said tubing, and means whereby all of said means are caused to operate in a predetermined sequence.
4. An apparatus for forming a plurality of flares from a length of glass tubing comprising a carrier supporting a plurality of substantially vertically disposed holders each adapted to receive a length of glass tubing, means for rotating said carrier step by step, a fusing means, a flanging means, and means for severing a section of tubing comprising a flange without substantially narrowing the passage therethrough, all disposed in the path of travel of the ends of said tubing, and means whereby all of said means are caused to operate in a predetermined sequence.
5. An apparatus for forming a plurality of flares from a length of glass tubing comprising a carrier supporting a plurality of holders each adapted to receive a length of glass tubing, means for rotating said carrier step by step, means for rotating said holders, a fusing means, a flanging means, and means for severing a section of tubing comprising a flange without substantially narrowing the passage therethrough, all disposed in the path of travel of the ends of said tubing, and means whereby all of said
- means are caused to operate in a predetermined sequence.
6. An apparatus for forming a plurality of flares from a length of glass tubing comprising a carrier supporting a plurality of holders each adapted to receive a length of glass tubing, means for rotating said carrier step by step, a fusing means, a flanging means comprising a pencil and rotating means therefor, and means for severing a section of tubing comprising a flange without substantially narrowing the passage therethrough, all disposed in the path of travel of the ends of said tubing, and means whereby all of said means are caused to operate in a predetermined sequence.
7. In a device for flanging glass tubes, the combination of a support, a flanging pencil pivotally supported thereon, means for advancing said support and for tilting said pencil to cause it to enter a tube longitudinally thereof, means for thereafter causing said pencil to tilt transversely of said tube, and means for rotating said support during the flanging operation.
8. In a device for flanging glass tubes, the combination of a support, a flanging pencil pivotally supported thereon, means for advancing said support and for tilting said pencil to cause it to enter a tube longitudinally thereof, means for thereafter causing said pencil to tilt transversely of said tube, and means for rotating said support during the flanging operation.
9. In a device for flanging glass tubes, the combination of a support, a flanging pencil pivotally supported thereon, means for advancing said support and for tilting said pencil to cause it to enter a tube longitudinally thereof, means for thereafter causing said pencil to tilt transversely of said tube, and means for removing glass which may lodge on said pencil.
10. In a device for flanging glass tubes, the combination of a support, a flanging pencil pivotally supported thereon, means for advancing said support and for tilting said pencil to cause it to enter a tube longitudinally thereof, means for thereafter causing said pencil to tilt transversely of said tube, means for retracting said support, means operated during said retraction for stripping lodged tubing from said pencil, and means for rotating said support during the flanging operation.
11. An automatic flare making machine comprising a rotatable carrier, means for intermittently rotating said carrier, a plurality of rotatable chucks for holding glass tubing on said carrier, means for rotating said chucks, means for fusing an end of said glass tubing, flanging mechanism for flanging the fused end of said glass tubing, means for bringing said flanging mechanism into engagement with said fused end, means for releasing each of said chucks to feed the said tubing therethrough, means for receiving said tubing to gauge the amount thereof fed through said holder, means for advancing said receiving means toward said tubing substantially at the time of release to prevent shock thereto, means for returning said receiving means to the gauging position, means for severing said flanged

end from said tubing, and means for causing the operation of the several aforesaid mechanisms in a predetermined sequence and for predetermined intervals.

- 5 11. In a flanging machine for glass tubing, the combination of a plurality of holders each adapted to support a length of glass tubing in a substantially vertical position with an end thereof projecting from
10 said holder, a fusing means, a flanging means comprising a pencil normally disposed in a substantially vertical position and pivotally mounted on a support, a carrier for said holders, a driving means for

advancing said carrier and bringing the 15 ends of each of said lengths of tubing successively to said fusing means and then to said flanging means, and means operating in proper timed relation to said driving means for thereafter reciprocating said support to cause said pencil to enter said tube end and to thereafter swing toward the horizontal.

In witness whereof, we have hereunto set our hands this 1st day of July, 1921.

FRANCIS J. RIPPL.
FRANK J. MALLOY.
